UNITED STATES PATENT OFFICE.

HARRY A. BACON, OF BRANCHVILLE, MARYLAND.

ADJUSTABLE RISER FOR SPRING BED-BOTTOMS.

No. 924,217.

Specification of Letters Patent.

Patented June 8, 1909.

Application filed January 28, 1909. Serial No. 474,812.

To all whom it may concern:

Be it known that I, HARRY A. BACON, a citizen of the United States, residing at Branchville, in the county of Prince George and State of Maryland, have invented certain new and useful Improvements in Adjustable Risers for Spring Bed-Bottoms, of which the following is a specification.

My invention relates to beds, and more particularly to supports for bed bottoms.

One object in view is to provide a device, simple and cheap in construction, for holding bed bottoms in an elevated position on the beds where they are used, to prevent the beds from having that low, squat appearance, so objectionable and yet so common, in all cases where the ordinary low iron and brass bedsteads are supplied with woven or National spring bed bottoms of ordinary construction.

In other words, I propose to give a bed the elegant appearance of being provided with box springs.

Another object is to provide a device of the character just mentioned, which shall be adjustable, whereby to raise or lower the bed bottom to any height desired, relatively to the bed with which it may be used.

A still further object is to provide a device for use with a spring bed bottom, whereby the full width of a mattress used therewith will be yielding and therefore available for use; the arrangement being such that when the sides of the mattress are forced downward, the portion of the springs supporting said sides can move downward as far as may be required without coming in contact with either the side rails of the bed or the side rails of the spring-bed-bottom.

Other objects will appear in the subjoined description.

The invention consists in certain novel constructions and combinations of parts, as will be hereinafter described and claimed.

The preferred form of my invention consists of a bed-bottom support or riser preferably secured to the bed-bottom and vertically adjustable thereon, and adapted to be used with beds of different widths.

In the accompanying drawings, Figure 1 is a perspective view of a bed provided with my improvement. Fig. 2 is a side or edge elevation of my device attached to the tubular iron side rail of a spring bed bottom.

Fig. 3 is a front elevation of Fig. 2. Fig. 4 is a view in elevation illustrating the adapta-

bility of my device for permitting the side rails of a spring bed bottom to be located well in from the ends of the end rails; and also shows its adaptability for use with beds of greatly varying widths. Fig. 5 is an elevation showing my device in a modified form, and in different positions on the tubular rail of a spring bed bottom. Fig. 6 is a perspective view of one form of my improved riser. Fig. 7 is a perspective view of an adjusting block that may be used with my device when the same is attached to the side rails of an iron bed bottom. Fig. 8 is a modified form of my adjustable riser provided with means for engaging the rail of a spring bed bottom, without the adjusting block illustrated in Fig. 7. Fig. 9 is a perspective view of a spring bed bottom having a wooden frame of desirable construction which, when supplied with my improvement, is specially adapted for use on an iron bedstead. Fig. 10 is a fragmentary perspective of a spring bed bottom having a wooden frame of ordinary construction. Fig. 11 is a fragmentary end elevation of Fig. 9. Fig. 12 is a fragmentary end elevation of Fig. 10. Fig. 13 shows an ordinary wooden spring bottom frame (such as is illustrated in Figs. 10 and 12) provided with my improved riser. Fig. 14 illustrates three of the four positions in which my improved riser may be attached to the rail of a spring bed bottom, the dotted lines showing it in two positions. Fig. 15 is a perspective of the form of my device usually employed with wooden bed bottom frames; and Fig. 16 shows my device attached to the bed rail (instead of the spring rail), and adjustable thereon, to give the bed bottom any desired degree of elevation.

A, is a metallic bed-steed of ordinary construction, having an iron-framed spring bed-bottom provided with my improvement.

The numeral 1 indicates the vertical or body section of my improved riser; 2, the horizontal or foot section; and 3, the bottom or heel section. In Fig. 6 the device is shown as provided with a second foot 2^x extending in the opposite direction to the foot 2. The vertical section 1 is provided with the longitudinal slot 1^a, and preferably with the transverse corrugations 1^b on one or both of its sides. Both the horizontal sections, 2, and 2^x, may be formed either integral with the body section 1, or may be formed of a separate piece adjustably secured thereto,

and when either one of them is formed in this latter manner, it is provided at its inner end with a rib 2^b adapted to fit the corrugations 1^b , and a short right-angled section 3^a which 5 may extend either upwardly or downwardly as the needs of each case may require or as fancy may dictate, and which when it extends downwardly forms a part of the heel 3 of the device, as in Fig. 5. This upwardly 10 or downwardly extending portion 3^a is provided with an opening 3^b (shown in dotted lines in Fig. 5) adapted to register with the longitudinal slot 1^a of the vertical section of the riser, and is secured to said section by the 15 bolt 4 , the slot 1^a in this form of the device being longer than in the form illustrated in Figs. 2, 3, and 6.

In attaching my improved riser to the tubular rail of a spring bed bottom, I interpose the adjusting block 5 between the riser 20 and the rail. One side of this adjusting block is concaved as at 5^a , to fit the curvature of the rail, and the other side is provided with ribs 5^b adapted to fit the corrugations 25 1^b of the riser; while at its center it has the opening 5^c adapted to register with the slot 1^a of the riser. Through this opening 5^c and the slot 1^a in the riser and a horizontal opening A^1 in the spring-rail A^3 , passes the bolt 6 30 which locks these three parts in rigid engagement with each other. The concavity of the adjusting block prevents it from rotating on the tubular rail A^3 ; and the ribs 5^b being locked in engagement with the corrugations 35 1^b of the riser prevent the riser from rotating on the bolt 6 . The principle of the adjusting block 5 is that one side of it shall fit the riser to prevent the rotation of these two parts 40 relatively to each other, and that the other side shall be formed to fit that part of the bed or bed bottom to which the device is to be attached, whatever the shape of that part may be. The adjusting block 5 is not needed with my riser when it is attached to a 45 wooden rail, since the corrugations sink into the wood and securely hold the riser in position thereon.

The foot sections of my device usually rest upon the bed rails A^2 to support the mattress 50 in elevated position upon the bed, while the heel portions 3 prevent the bed bottom from having unnecessary lateral movement relatively to the bed.

Referring to Figs. 4 and 5, the opening 3^b 55 and the rib 2^b are spaced apart a distance equal to the distance from one corrugation to the next; whereby the securing nut 4^a will always be brought into engagement with one of the flat faces 1^c which alternate with the corrugations 1^b of the riser. The corrugations 1^b as they appear on opposite sides of the riser in Figs. 4 and 5, are zigzagged to give the deepest possible corrugations with the least possible weakening of the metal.

65 The iron spring-bed-bottom frame illus-

trated in whole and in part in Figs. 1 to 5 of the drawings in connection with my improvement, is of ordinary construction, and consists of the ordinary parts, and therefore need not be further described here.

70

Fig. 4 shows the vertical section 1 of my device provided with two adjustable feet, 2^a and 2^{ax} , the former extending outwardly and the latter inwardly. The foot 2^{ax} is longer than the other, since it is underneath 75 the bed bottom out of the way, and may therefore extend inwardly as far as may be desired. This foot is provided with a longitudinal slot 2^{ay} (shown in dotted lines), and in this slot is a bolt 2^{az} provided with adjusting nuts z , and having its lower end a^z bent at an angle, or curved upwardly, as illustrated in dotted lines, if preferred. This bolt is adjustable back and forth in the slot 2^{ay} , to adapt a bed bottom, in cases of emergency, to be used with a bed much narrower than the bed bottom itself; and when the bent section a^z is turned underneath the bed rail as shown, the bed bottom cannot tilt even though it should project far over the 90 sides of the bed. The foot 2^a only projects out approximately flush with the side of the bed bottom, and therefore need not be removed if the bed bottom be placed on a much narrower bed with the inwardly extending foot 2^{ax} in engagement with its side rail. Special attention is called to the fact that if the foot 2^{ax} be turned outwardly or the foot 2^a lengthened, the side rails A^3 of the bed bottom may be moved inwardly so far 95 toward each other, that the end rails to which they are secured will be so strongly braced by them that they cannot be strained and bent at their centers by the tension of the springs.

105

Fig. 6 shows the form of my device illustrated in Figs. 2 and 3 in perspective, with the foot 2^x added. The slot 1^a in this form of the device does not extend downwardly as far as in the form illustrated in Figs. 5 and 8.

110

Fig. 7 is a perspective of the adjusting block 5 , showing the ribs and the central opening of the block.

Fig. 8 shows the vertical section of my riser provided with a broad corrugation 1^d 115 adapted to fit the side rail A^3 of the bed bottom to hold the riser against rotation thereon without the adjusting block 5 .

Fig. 9 shows a simple and desirable form of 120 wooden frame for spring bed bottoms—a form however, only adapted, at present, for use with wooden beds, but which, when supplied with my improvement, is equally well adapted to iron beds.

Fig. 10 illustrates an ordinary spring bed-bottom B in operative relation to the bed rail A^2 . It will be noticed in this form of bed bottom that the side rails B^1 are necessarily set in some distance from the ends of the end rails B^2 of the frame, so that the outer ends 125 130

of the rails B^2 may rest upon the side rails A^2 of the bed. This brings the bed bottom just slightly above the bed rails, and makes a low squat-looking bed. Moreover, the 5 outer strands of the spring are just above the top of the bed rail, and the strands next to them are just above the side rail B^1 of the bed bottom, so that the outer edge of the 10 spring bottom (and a mattress resting thereupon) can only spring down very slightly till it comes in contact with these rails, and is therefore for all practical purposes not 15 resilient at all. Furthermore, when any one lies upon this practically solid or unyielding portion of the mattress, or sits upon the side 20 of the bed, the side strands of the springs are brought into such forcible engagement with the side rail of the spring frame and with the bed rail that they are elongated and as a result sag, which for manifest reasons is very 25 objectionable. Note the freedom from all these undesirable features in my improved construction and arrangement illustrated in Fig. 9.

25 Figs. 11 and 13, as compared with Fig. 12, show how a bed bottom is elevated above the bed rails by the use of my device; and then (in Fig. 9) the side rails C^1 of frame C are at the ends of the end rails C^2 , so that when a 30 person lies or sits upon the side of the bed, the natural tendency of the springs to move in slightly when they are sprung down at the edge of the bed, will cause them to miss the side rails C^1 , and the springs are so far above 35 the bed rails that they can never be sprung down into engagement with them.

The modified form of riser 7 which I employ with wooden frames is provided preferably with two longitudinal slots 7^a ; and the 40 corrugations 7^b , which are intended for engagement with wooden rails, are made sharper. In this form of the device the foot and heel portions of the device are identical with those in the other forms and may be 45 adapted to be adjusted in the same way as the form illustrated in Figs. 4, 5, and 8. Fig. 14 shows this modified form of riser provided with corrugations on both its sides, and also shows, as does Figs. 4 and 5, how 50 my riser may be employed to adapt the same spring bed bottom for use on narrower or wider beds. By referring to these figures it is manifest that if the riser be placed on the inside of the frame (as shown in Figs. 5 and 55 14 in dotted lines and in Fig. 4 in full lines) with the foot turned inward to the left, that a wide spring bed bottom and mattress may be used on a much narrower bed than the bed bottom and mattress in question would 60 ordinarily require. It is further apparent that with my riser attached as shown in full lines in Figs. 4, 5, and 14, a narrow bed bottom and mattress may be used on a bedstead wider than the bed-bottom.

65 Fig. 15 is a perspective view of one form of

the riser used with wooden bed-bottom frames; but one of the slots may be omitted if desired.

Fig. 16 shows how my riser may be adjustably attached to the bed rail, in inverted 70 position, with the foot portion directly supporting the bed-bottom frame.

Having thus fully set forth the principles embraced in my invention, and having shown means practically embodying the 75 same what I claim as new and desire to protect by Letters Patent is:—

1. The combination with a bed and a co-operating bed bottom of devices interposed between said parts for supporting the bed bottom on the bed, said devices being adapted to be secured to one of said co-operating parts in different vertical positions thereon, to raise or lower the bed bottom bodily.

2. The combination with a bed and a bed 85 bottom, of devices co-operating with said parts to support the bed bottom on the bed, each of said devices having a main member adapted for vertical adjustment relatively to one of said co-operating parts and a lateral 90 member adjustable relatively to the main member.

3. The combination with a bed bottom, of devices for supporting the same in an elevated position on a bed, and means for securing 95 said devices to the bed bottom in different vertical positions thereon to raise or lower the bed bottom bodily.

4. The combination with a bed and a bed bottom, of risers co-operating with said parts 100 to support the bed bottom on the bed, each of said risers having a main member provided with a vertical slot to adapt the same for vertical adjustment upon one of said co-operating parts, and a lateral member for 105 engaging the other of said parts.

5. The combination with a bed-bottom, of a riser having a vertical member for engaging the bed-bottom; and a lateral member for 110 engaging and resting upon a bed rail; and means for adjusting said vertical member of the riser on the bed-bottom.

6. A device of the character described, comprising a vertical section adapted to be secured to a bed-bottom, and a lateral section 115 for engaging and resting upon a bed; and a section extending below said lateral extension, to prevent lateral movement of the bed-bottom on the bed.

7. A device of the character described, having a body section adapted to be secured to a bed bottom; a foot section adapted to engage a bed rail to support the bed bottom thereupon; and an adjustable stop in said foot section to prevent the lateral movement 125 of the bed bottom upon the bed, said stop being adapted to be brought into interlocking engagement with the bed rail.

8. A device of the character described, comprising a vertical section adapted to be 130

secured to a bed-bottom, and a lateral section for engaging and resting upon a bed; a section extending below said lateral section, to prevent lateral movement of the bed-bottom on the bed; and means for adjusting said device to raise or lower the bed-bottom relatively to the bed.

9. A device of the character described, comprising a vertical section provided with 10 a slot for adjustable engagement with the bed bottom; and a lateral section, for engaging the bed.

10. A device of the character described, comprising a vertical section provided with 15 a longitudinal slot and transverse corrugations for adjustable and rigid engagement with the bed bottom; and a lateral section, for engaging the bed.

11. A device of the character described, 20 comprising a vertical section provided with a longitudinal slot and transverse corrugations for adjustable and rigid engagement with the bed bottom; a lateral section for engaging the bed; and a heel section projecting below the lateral section, to prevent lateral movement of the bed bottom upon the bed.

12. In devices of the character described, 25 a riser having a portion adapted to engage the rails of a bed; and a portion provided with transverse corrugations; and an adjusting block adapted to be interposed between the riser and a bed-bottom, said adjusting block having on one of its sides ribs 30 adapted to coöperate with the corrugations of the riser, and on its other side being shaped to fit the portion of the bed-bottom to which it is to be attached.

13. In devices of the character described, 35 a riser having a vertical section provided with a longitudinal slot and transverse corrugations; a foot section at approximately right angles to the vertical section; and an adjusting block having an aperture adapted 40 to register with the slot in the vertical section of the riser, and provided on one of its sides with ribs adapted to coöperate with the corrugations in the riser, and concaved on its 45 other side, said foot section being adjustable 50 on the vertical section.

14. In devices of the character described,

a riser having a vertical section provided with a longitudinal slot and similar transverse corrugations on both its sides; a foot section adjustable on the vertical section and 55 provided with a rib to fit the corrugations on said vertical section; an adjusting block having an aperture adapted to register with the slot in the vertical section of the riser, and provided on one of its sides with ribs 60 adapted to fit and coöperate with the corrugations of the riser, and concaved on its other side to fit the curved rail of a bed-bottom; and a heel section projecting below the 65 foot section of the riser.

15. In devices of the character described, 70 a riser having a vertical section provided with a longitudinal slot and similar transverse corrugations on both its sides, the corrugations on opposite sides being zigzagged 75 relatively to each other; an adjustable foot section, on the lower end of the vertical section of the riser, provided with a rib to fit the corrugations on said vertical section; an adjusting block on the upper end of the riser 80 having an aperture adapted to register with the slot in said section and provided on one of its sides with ribs adapted to fit into said corrugations of the riser, and concaved on its 85 opposite side to fit the curved rail of a bed-bottom; and a heel section at the base of the foot section of the riser, said heel section having an aperture adapted to register with the slot in the vertical section, said aperture of the heel section being spaced from the rib of the foot section a distance equal to the space 90 between the corrugations of the vertical section.

16. A device of the character described, 95 having a body section adapted to be secured to a bed-bottom; a foot section adapted to engage a bed rail to support the bed-bottom thereupon; and an adjustable stop in said foot section to prevent the lateral movement of the bed-bottom upon the bed.

In testimony whereof I have signed my name to this specification in the presence of two subscribing witnesses.
